UNITED STATES PATENT OFFICE.

ALFRED L. FLOOD, OF CHICAGO, ILLINOIS, ASSIGNOR OF ONE-HALF TO
WILLIAM L. WEBER, OF CHICAGO, ILLINOIS.

INTERLOCKING CARPET OR FLOOR-COVERING.

SPECIFICATION forming part of Letters Patent No. 713,420, dated November 11, 1902.

Application filed March 3, 1902. Serial No. 96,391. (No model.)

To all whom it may concern:

Be it known that I, ALFRED L. FLOOD, a citizen of the United States, residing at Chicago, in the county of Cook and State of Illinois, have invented a certain new and useful Improvement in Interlocking Carpets or Floor-Coverings, of which the following is a specification.

My invention relates to interlocking car-
10 pets or strips of floor-covering, and has for
its object to provide convenient means for
covering floors with interlocking materials,
the same to be prepared in strips or in strips
in combination with tile-sections and adapted
15 to be used either from the roll or in patterns
built up to fit by surfaces or areas of prepared
plans and dimensions.

My invention is illustrated in a sense dia-
grammatic in the accompanying drawings,
20 wherein—

Figure 1 is a plan view of a floor-covering
composed of strips taken from the roll. Fig. 2
is a plan view of a floor with the central areas
between doors covered with tile-sections of
25 different patterns and the corner-section of
the room covered with strips which interlock
together and also interlock with the tiles.
Fig. 3 is a plan view of a floor-covering pre-
pared for an irregular floor-space and con-
30 sisting of a central pattern portion of tile, if
desired with border-sections, shaped to fit the
room and all the parts interlocking. Fig. 4
is a cross-section showing the interlocking
strip carried up to form the base-board or re-
35 turn at the edge of a room.

Like parts are indicated by the same letters
in all the figures.

A A are sections of strips of interlocking
material, and they may be made of any de-
40 sired width from a few inches to a few feet
and of any desired length. They may have
interlocks (indicated at B B) on both sides
and either or both ends, as may be desired.
C C are strips of like material having the in-
45 terlock on but one edge or side. In Fig. 1 I
have shown these strips arranged so as to
cover a floor-section, leaving the outer mar-
gin free from the interlocks. It would in such
case come up against the base-board and can
50 be nailed or secured, if desired.

D D are narrow border-strips, which may

be used across the ends or along the sides of
the larger or central strips or mass of tiling.
These strip borders may be mitered and inter-
locked, as indicated at E, the miter-lock be-
ing cut as the material is laid or the material
being furnished in rolls with mitered ends
and interlocks. These border-strips may be
finished as shown at the left in Fig. 2, the
end of one strip abutting against the side of
the other and the two interlocking, as indi-
cated at F. The border-strips thus interlock
with the body-strips, and the body-strips, as
indicated, interlock with the sections of tile
G G. These sections of tile may be of any
kind of tile or they may not be true tile.
They may be composed of material cut and
shaped and with the tile impressed simply as
an ornamental design.

J J are a series of border-strips to make
pattern-work, and they may be of any de-
sired color, size, or shape. As indicated at
K, they are carried around an angle, so as to
conform to the outline of the room, or, in the
case illustrated, the outline of a palace-car.

L is the central body of tile or ornamental
work.

M is a return-strip interlocked at N to the
strip A and at its upper end coming under
the molding O. A plan view of this strip
would show somewhat like the strips D D in
Fig. 2, for the upper edge of the strip M is
covered by the molding.

P indicates strips which may be attached
to the bottom of the sections.

Strips or tiles or a continuous strip cover-
ing the whole bottom of a given arrangement
of parts can be used to hold the several sec-
tions together when they have been arranged
on the work-floor to suit or fit a given area.
I have used the term "strips" to indicate
these larger sections; but I use this term in
a very general sense to mean large and par-
ticularly long sections of the covering ma-
terial.

There are various other ways in which my
invention may be reduced to practice, and I
have only endeavored in the foregoing de-
scription and illustrations to show some of
the most important uses to which it can be
put and some of the most desirable arrange-
ments of the several parts which combine to-

gether to contain my improvement in actual use.

The interlocking strips can be of any size, shape, or length and with the interlocks on 5 one or both sides or ends, as may be required. The ends may also be mitered or shaped, and the strips thus may be carried off on angles or about curves, as suggested. The strips may be used with or without tiles, and either 10 tiles or strips may be of any desired color or with any desired pattern thereon. Of course when the tiles and strips are used together the proportions of the several parts must be such that the interlocks associated with a row 15 of tiles will correspond with similar interlocks on the strip.

The strips, with or without the tile sections or centers, may be arranged in the work-room to fit approximately the apartment or floor- 20 space to be treated, and then the parts can be held together—as, for example, by the back strips, which are shown at P in Fig. 4. Such finished carpet or covering can then be placed in the proper room and the exact final measurements be taken and a new border-strip be 25 added, the same being cut or bent up at the corners, as the case may be, to make the complete carpet a fit for the particular floor in question. I do not wish, therefore, to be limited to the particular forms, arrangements, or combinations of these several parts.

The use and operation of my invention are as follows: The strips of interlocking material will be made and may be shipped and 30 sold and used from the roll like ordinary carpeting, and thus a floor which is to all intents and purposes a tile-floor may be laid down without any difficulty and of any desired material, for my invention is applicable 35 to any of the ordinary materials which possess sufficient strength and body to make the interlocking effective and by persons who are not particularly skilful in connection with such matters. Moreover, the return edge 40 can in like manner be made with very little difficulty, because the last strip, either of the width as it comes from the factory or as cut by the person who lays the floor, can be bent up at the corner of the room and carried underneath a molding, so as form the base- 45 board. It is only necessary then to cement or close the spaces of the interlock, whereupon a floor capable of holding two or three inches of water without leaking is formed. 50 The junctions at the corners can be made in any desired manner, according to the conditions of each case. When a given section of flooring has been laid down from the roll, it is cut off the right length, like carpeting, and 55 another section taken. When finally the roll is exhausted, if its end is made with interlocking devices the next roll can be interlocked at ends and sides and be laid down in like manner, and thus the work may be continued to the end. If the end of the roll is not 60 provided with the interlocking devices, it will

have to be cut with a hand tool or die provided for that purpose. If, as in the cases illustrated in Figs. 2 and 3, a tile-section floor is desired, it is only necessary to lay down these 70 tile-sections in the usual manner and form without mutilating the tiles, thus leaving projecting on the edges or margins of such tile-section a series of interlocking devices, which will be found to register with the like 75 interlocking devices of the margins and edges of the strips. Thus the strips may then be laid alongside of the tiling and a complete floor may be made. Of course the tiling may be inside or outside of the strips, as the case 80 may be. As previously suggested, these sheets may be made of any desired material. They might, of course, be made of rigid or hard material; but my preference is to make them of yielding material which will roll. 85 The tiles and strips, if used together, need not, of course, be of the same material. It is only necessary that their interlocking parts should be made to fit each other.

I claim—

1. A floor-covering comprising a series of long strips with marginal interlocking devices adapted to prevent them from separating laterally and edge strips which are turned up along the edges of the room. 90

2. A floor-covering comprising a series of strips with marginal interlocking devices and sections of tiling with interlocking devices adapted to engage those of the strips, such interlocks adapted to prevent the parts from 100 separating laterally.

3. A floor-covering comprising a body of interlocking tile with marginal interlocking devices, and a series of strips with marginal interlocking devices engaging the interlocking 105 devices of the adjacent tiles, such interlocks adapted to prevent the parts from separating laterally.

4. A floor-covering comprising a body of interlocking tile with marginal interlocking devices, and a series of strips with marginal interlocking devices engaging the interlocking devices of the adjacent tiles, and border-strips 110 with interlocking devices to engage those of the larger strips, such interlocks adapted to 115 prevent the parts from separating laterally.

5. A floor-covering comprising a body of interlocking tile with marginal interlocking devices, and a series of strips with marginal interlocking devices engaging the interlocking 120 devices of the adjacent tiles, and border-strips with interlocking devices to engage those of the larger strips, such interlocks adapted to prevent the parts from separating laterally and said borders turned up at the edges of 125 the room.

6. A floor-covering comprising a body of strips having marginal interlocking devices, the whole held permanently together and of a pattern to approximately fit the room, with 130 border-strips having interlocking devices adapted to fill the spaces between the body

portion and the walls, such interlocks adapted to prevent the parts from separating laterally.

7. A floor-covering comprising a central body of tile with interlocking edges, a series of strips thereabout with marginal interlocking devices adapted to engage each other and the central tile-body, means for holding all of these parts together and a removable border-strip to engage the interlocking devices and fill the room, such interlocks adapted to prevent the parts from separating laterally.

8. A floor comprising interlocking tile-sections and strips suitably associated together and shaped so as to form a body of covering material approximately the size and shape of the floor to be covered with exterior interlocking devices and with interlocking border-strips adapted to complete the floor-covering for the entire floor, such interlocks adapted to prevent the parts from separating laterally.

9. A floor comprising interlocking tile-sections and strips suitably associated together and shaped so as to form a body of covering

material approximately the size and shape of the floor to be covered with exterior interlocking devices, and means for holding these several parts together in a relatively permanent manner before they are laid on the floor, with interlocking border-strips adapted to complete the floor-covering for the entire floor and to be laid in position when the principal body of the covering has been placed in its approximately predetermined position on the floor, such interlocks adapted to prevent the parts from separating laterally.

10. As a new article of manufacture for floor-covering, strips of covering material of great length relative to their width, said strips provided with marginal interlocking recesses and projections adapted to prevent said strips from separating laterally one strip from the other.
